CHAIR CARRIER

Ivan L. Loesch, Huron, S. Dak., assignor to Spacer Furnishings Corp., Huron, S. Dak., a corporation of South Dakota

Filed Feb. 5, 1964, Ser. No. 78,535

Term of patent 14 years

(Cl. D14—3)

FIG. 1 is a perspective view of a chair carrier showing my new design;

FIG. 2 is a side elevational view thereof;

FIG. 3 is a top plan view thereof;

FIG. 4 is a bottom view thereof;

FIG. 5 is a front elevational view thereof; and

FIG. 6 is a rear elevational view thereof.

The side opposite that shown in FIG. 2 is a mirror image of the side shown.

I claim:

The ornamental design for a chair carrier, as shown and described.
